UNITED STATES PATENT OFFICE.

ENOCH WHALLEY, OF WILLIMANSETT, MASSACHUSETTS.

TRUCK.

1,253,757.

Specification of Letters Patent. Patented Jan. 15, 1918.

Application filed May 2, 1917. Serial No. 166,001.

To all whom it may concern:

Be it known that I, ENOCH WHALLEY, a citizen of the United States of America, residing at Willimansett, in the county of 5 Hampden and State of Massachusetts, have invented a new and useful Truck, of which the following is a specification.

My invention relates to improvements in trucks of the so-called elevating type, where- 10 in a longitudinal movement is converted into a rising or falling movement, according to the direction of such longitudinal movement, for use in hauling goods about by hand, and consists in general of certain pec- 15 culiar truck sections and the operating means therefor, the latter including means wherewith the upper section is raised from the under section or elevated and lowered or depressed, together with such auxiliary and subsidiary parts and members as may be 20 necessary or desirable in order to render the truck complete and practicable and serviceable for the purposes for which it is intended, all as hereinafter set forth.

25 The primary object of my invention is to produce a simple, both structurally and oper- atively, comparatively inexpensive, strong and durable, low-down, and highly efficient truck, for use in raising goods or material truck, for use in raising goods or material 30 from the support therefor on the floor, or with such support from the floor, hauling such goods or material to the desired local- ity, and there lowering and depositing the same.

35 A further object is to provide, in the direct-acting raising and lowering means or mechanism of such a truck, means for equal- izing the load as it were.

Another object is to provide such a truck 40 with powerful and self-controlling or self- locking actuating mechanism, which at the same time is of such a nature that it is com- paratively easy to operate, and is also prac- tically uniform in operation and under- 45 varying stresses, so that the variation in the force necessary to be exerted by the oper- ator is scarcely perceptible. Co-operating with this actuating mechanism is the above- mentioned direct-acting raising and lower- 50 ing means whereby the equalizing effect is produced, and such means contributes to the success and efficiency in certain respects, of said actuating mechanism, as will subse- quently more clearly appear.

55 The equalizing effect, through which the operator with comparatively little effort on

his part is able to handle easily and success- 60 fully a very heavy load, and to which refer- ence was made above, may be said to be inher- ent in the raising and lowering mecha- nism, and more especially in the direct-act- 65 ing portion thereof. The load in being ele- vated is started upward slowly and con- tinues to rise slowly, speed not being re- quired or desired, so that the force required 70 to elevate the load is approximately uniform throughout the lifting operation, and, con- versely, the same thing is true when the load is lowered, force of a nearly uniform character being then as always in evidence. 75 Thus both the raising and lowering opera- tions, from start to finish, are performed under conditions which require the expendi- 80 ture of an approximately uniform amount of force, so that little or no extra effort is 85 called for or force involved either in start- ing the load upwardly or in restraining the load as it approaches the limit of its down- ward travel. And this apart from the worm drive which is a factor of the actuating 80 mechanism presently to be described.

Still another object is to so construct a truck, of the type in question, that the steering elements including the tongue or handle are entirely independent of the raising and 85 lowering elements, wherefore there is and can be no interference of any kind between them. This obviously is an important ad- vantage.

The truck, while itself light in weight, is 90 capable of handling a load of great weight; and said truck, although having an ade- quate range of elevation, is sufficiently low, when the upper section is down in its low- 95 est position, to be operated in connection with a stack of goods or material that is supported very close to the floor.

Other objects and advantages will appear in the course of the following description.

A preferred embodiment of my invention, 100 whereby I attain the objects and secure the advantages of the same, is illustrated in the accompanying drawings, and I will proceed to describe said invention with refer- ence to said drawings, although it is to be 105 understood that the form, construction, ar- rangement, etc., of the parts in various as- pects may be modified, without departure from the spirit of the invention, so long as the scope of the claims be not exceeded. 110

In the drawings, in which like numerals designate like parts throughout the several

views, Figure 1 is a top plan of a truck which embodies the invention as aforesaid, the upper section being in its low position, and the forward portion of the handle or tongue broken off; Fig. 2, a side elevation of said truck, with said upper section down and said tongue broken off as before; Fig. 3, a fragmentary detail in side elevation, showing the disposition of the links when 10 said upper section is elevated to its fullest extent; Fig. 4, a front elevation of the truck, the parts being disposed as in the first two views, and the tongue in section; Fig. 5, a cross-section through said upper section, taken on lines 5—5, looking in the direction of the associated arrow, in Fig. 1, the under section of the truck being represented by dot-and-dash lines; Fig. 6, a cross-section through the truck, on lines 20 6—6, looking in the direction of the associated arrow, Fig. 1, and, Fig. 7, a detail of the worm members.

The truck, in the present form, comprises an under section or carriage, which is a body or frame mounted on rolls or wheels; a superimposed or upper section or platform capable of moving longitudinally and upwardly relative to said carriage; equalizing lifters, in the form of links of peculiar construction, which constitute the direct means whereby said platform is raised and lowered; and actuating means for drawing said platform forward on said carriage, or forcing the latter backward under the former, as the case may be, to elevate said platform.

The body or frame of the carriage as here presented comprises two angle-iron side pieces 1 connected at their front ends by an inverted U-shaped head piece 2, and connected near their rear ends by a cross bar 3 which has trunnions 4—4 at the ends. The aforesaid support consists of two uprights 7 which rise from the head 2 and are connected at the top by a cross bar 8. The head 2 has at the top a central, forwardly-extending, flat projection 9. A lug 10 projects outwardly from the bottom edge of each side piece 1 behind the head 2, and a lug 11 projects outwardly from the bottom of the cross bar 3 beyond each end thereof. A cross rod or bar 12 is introduced between the side pieces 1 immediately behind the head 2, and such bar has trunnions 13—13 at the ends which extend through said side pieces and project beyond the same. The uprights 7 limit the forward movement of the platform or the rearward movement of the carriage, relatively, as will presently more clearly appear. Two pairs of links 14 60 are loosely mounted on the two pairs of trunnions 13 and 4, and a pair of wheels 15 is loosely mounted on said trunnions 4 outside of said links thereon.

The wheels 15 support the carriage at the 65 rear end, and said carriage is supported at

the front end by a swivel 16 and a pair of wheels 17, the projection 9 resting directly on said swivel and the latter being rotatably secured thereto by a kingbolt or kingpin 18 in the usual manner. The wheels 16 70 are mounted on an axle 19 carried by the swivel 16. A handle or tongue 20 is pivotally attached at its rear end to the swivel 16, as represented at 21.

The platform as here presented comprises 75 two side pieces 22 having downwardly-extending parts 23—23 intermediate of the ends of such side pieces, an angle-iron cross piece 24 connecting said side pieces back of their front terminals, and an angle-iron cross 80 piece 25 connecting said side pieces at their rear ends. The cross piece 24 is on top of the side pieces 22 and has two webs or lugs in which a shaft or rod 26 is mounted. The cross piece 25 is flush on top with the upper 85 edges of the side pieces 22. A shaft or rod 27 is mounted in the side pieces adjacent to the cross piece 25. Each of the rods 26 and 27 projects at both ends beyond the vertical planes of the outer faces of the side pieces 90 22, and mounted on such projecting terminals is a pair of links 28. The side pieces 22 with their parts 23, which latter form guide extensions, embrace the side pieces 1 95 at all times, so there can be no lateral movement of the platform relative to the carriage while the former is being raised or lowered or while it is in the elevated position. Thus the guide extensions 23 assist in steadyng the platform and holding it against sidewise 100 movement. When the platform is in its lowest position the cross piece 24, which extends beyond the side pieces 22, rests on the side pieces 1, and said side pieces 22 rest on the cross bar 3, which latter is under said 105 side pieces 1. The cross piece 24 serves as a forward stop for the load.

Although the axes of the rods 13 and 26 are respectively higher than those of the bar 3 and rod 27, the distance between the horizontal planes of the axes of the rod 13 and said bar is the same as the distance between the horizontal planes of the rods 26 and 27, so that the action of the links 14 and 28 at 110 both ends of the truck is the same. 115

Each link 14 is equal in length to each link 28, and adjacent links 14 and 28 have their contiguous terminals pivotally connected at 29. Contiguous terminals of the links 14 and 28 are inset to form transverse 120 shoulders or stops 30 which limit the rotative independent swing or movement of said links.

When the platform is down on the carriage, the rear ends of the links 14 lie on the 125 lugs 10 and 11, said lugs being so located that they then support said links in an approximately horizontal position, but with said rear ends slightly above the horizontal plane of the front ends of said links, so that the 130

upward swing of the links initially is facilitated. While the links 14 are in the position just described, the rods 26 and 27 are so located that the links 28 are disposed obliquely, extending upwardly and rearwardly, substantially as represented in Fig. 2. Assuming now that the carriage be held stationary and the platform drawn forward on said carriage, it is evident that said platform must be elevated, since the links 28 are caused to assume an upright or nearly upright position, and then the links 14 are caused to assume an oblique position corresponding to the position originally assumed by said links 14. This effect is brought about in the following manner: The links 28 first fulcrum on the pivots 29, and then, as said links approach the perpendicular, the shoulders 30 on the links 28 and 14 come into contact, interlocking the two sets of links, and said links 28, now fulcruming on said shoulders, cause said links 14 to swing upwardly on the trunnions 13. Before the rod 26 reaches the vertical plane of the rod 12, the cross piece 24 encounters the uprights 7, consequently the links can not be swung into position to lock the platform when elevated, but always support the elevated platform in such a manner that the same can descend by gravity so far as the links themselves are concerned. The links 14 and 28 carry up the platform until the latter arrives at the desired elevation see Fig. 3. These jointed-link lifters render it comparatively easy to start the platform with its load, and equalize the force required to carry said platform to the limit of its upward travel, the force being in a sense cumulative, as would not be the case if unjointed or single links were employed. Conversely or in reverse order the facts are the same, when the platform is permitted to move backward and downward. While the shoulders 30 are still in engagement the links 14 turn down on the trunnions 13 until the lugs 10 and 11 are encountered, and then the links 28 swing rearwardly and downwardly on the pivots 29 until the side pieces 22 and the cross piece 24 come to rest on the cross bar 3 and the side pieces 1, respectively. With these lifters the platform with its load could still be kept under complete control at the time said platform approaches the carriage and undue shock would still be prevented, even if other than friction controlling means, such as the worm members here present, were employed.

It should be noted that the shoulders 30 come into contact before the links 28 assume a position which would locate the rod 26 directly over the pivots 29, during the elevating operation. This is necessary in order that the axis of the rod 26 shall always be behind the vertical plane of the axis of the pivots 29, whenever the links 14 are bearing on the lugs 10 and 11, be-

cause, if said first named axis were directly in or forward of said plane, the platform in descending would be checked by the links 28 before the descent was more than half completed.

The actuating mechanism consists of a pair of pulleys 31 mounted on a shaft 32 journaled in the uprights 7, a pair of idlers 33 mounted on a shaft 34 also journaled in said uprights, a chain 35 passing over and down in front of said pulleys, and down in front of and under said idlers to the rod 26 to which said chain is fastened, a worm-wheel 36 mounted on said shaft 32, a worm 37 which intermeshes with said worm-wheel, and mounted on a shaft 38 which is journaled in a bearing bracket 39 attached to the underside of the cross bar 18, and an operating lever or crank rod 40 having a handle 41, and connected with said last-named shaft by a hub block 42. The pulleys 31 are of the ordinary indented type for a hoisting chain such as the chain 35. The ends of the chain 35 are made fast to the rod 26, while the middle slack portion of said chain hangs freely back of the pulleys 31, in the customary manner. The idlers 33 are a sufficient distance above the horizontal plane of the rod 26 to afford a downward incline to those parts of the chain 35 which extend from said idlers to said rod, so that the draft of said chain is upward. This is a valuable factor in facilitating the operation of elevating the platform, as will readily be seen.

The worm 37 is, of course, rotated by means of the crank rod 40, and in turn rotates the worm-wheel 36. When the worm-wheel 36 is rotated in the direction to raise the chain 35 in front, the platform is drawn forward and, through the medium of the links 14 and 28, elevated, and, when said worm-wheel is rotated in the opposite direction, said platform is permitted to move backward as it descends on said links. The rod 40 is adjustable in and through the block 42, so that the leverage of said rod may be increased or decreased accordingly as more or less power is needed to handle the load.

The piles or stacks of goods or material to be transported with my truck are supported from the floor at a sufficient height to enable said truck, while the platform is down, to be backed under any such stack or pile, and ordinarily portable benches are provided for the purpose, such benches in each case being raised, carried, and set down without removing the goods or material therefrom, although in some cases the supports are stationary and the material is transported without them.

Briefly, the operation of the truck as a whole is described as follows, starting with the parts disposed as in Figs. 1, 2, and 4: The truck is hauled by the tongue 20 to 130

the vicinity of the load to be moved and backed beneath the same. Then the crank rod 40 is rotated to raise the load, which includes the bench when present, from the 5 floor, on or with the platform, through the medium of the hoisting members and the lifters or links. The platform with its load having been elevated to the maximum 10 height, or to any lesser height, as may be desired, rests on the links 14 and 28, and is prevented from descending by the frictional resistance offered by the worm-members. Next the loaded truck is hauled by 15 means of the tongue 20 to the desired locality, and there the load is deposited, by rotating the worm members in reverse directions to permit the platform to descend onto the carriage and the bench to come to 20 rest on the floor, or the load in the absence of the bench to rest upon other supporting members, the operator through said worm members having absolute control of said platform throughout the descent of the latter. The truck is now drawn from 25 beneath the load and out of the way.

When the mechanism is operated to elevate the load and the platform comes into contact with the under surface of the load, there is usually so much frictional resistance that said platform is held stationary while the carriage moves backward on the wheels 17 and 15, but the desired result of elevating the platform and carrying the load up with it is attained just the same as 30 though the carriage were held stationary and the platform moved forwardly as well as upwardly.

By means of the jointed-link lifters the 35 raising and lowering operations may be easily and quickly performed under conditions that require the expenditure of an approximately uniform amount of force, and said lifters together with the worm-hoisting mechanism give into the hands of the operator full and complete control of the platform and load.

The movements of the swivel 16 and of the tongue 20 are in no way interfered with by the raising and lowering mechanism of the truck, such swivel and tongue being entirely independent of such mechanism, wherefore the greatest freedom is permitted to said swivel and tongue. It follows, therefore, that this truck can be moved about on 55 the floor with the utmost facility.

There are two lugs 43, on the bottom of the cross piece 24, which when the platform is down come into direct contact with the side pieces 1, in the present construction 60 and there also is a washer 44 on each trunnion 13 between the link 14 on said trunnion and the adjacent side piece 1.

What I claim as my invention, and desire to secure by Letters Patent, is—

65 1. In a truck, relatively movable upper and

under sections, a plurality of jointed-link lifters pivotally connected with said sections, and adapted to raise to its full height, as determined by the lengths of said lifters, said upper section when the latter is actuated in one direction or said lower section is actuated in the other direction, and actuating means for said sections relatively, such means being independent of said lifters. 70

2. In a truck, relatively movable upper 75 and under sections, worm-hoisting mechanism carried by said under section and connected with said upper section, and direct lifting means for said upper section, such means comprising jointed-link lifters pivotally connected with said sections, and adapted to raise said upper section when the latter is forced in one direction or said lower section is forced in the other direction. 80

3. In a truck, relatively movable upper 85 and under sections, a plurality of jointed-link lifters pivotally connected with said sections, and adapted to support said upper section, and worm-gear hoisting mechanism 90 carried by said under section and connected with said upper section.

4. In a truck, relatively movable upper 95 and under sections, pivotally-connected links pivotally connected with said sections, said links having projecting parts for mutual engagement during a portion of the movement of said links, and actuating means for said sections relatively.

5. In a truck, relatively movable upper 100 and under sections, pivotally-connected links pivotally connected with said sections, said links having projecting parts for mutual engagement during a portion of the movement of said links, and said under section 105 having lugs arranged to limit the movement in one direction of the joined terminals of said links, and actuating means for said sections relatively.

6. The combination, in a truck, of a carriage 110 provided with front-end supporting and guiding means, a superimposed platform, jointed links pivotally connected with said carriage and platform and adapted to raise the latter when the same is forced in 115 one direction or said carriage is forced in the other direction, and actuating means for said carriage and platform relatively, said first- and last-named means being independent of each other. 120

7. The combination, in a truck, of a carriage 125 provided with front-end supporting and guiding means, a superimposed platform, jointed links pivotally connected with said carriage and platform, and adapted to raise the latter when the same is forced in one direction or said carriage is forced in the other direction, and worm-hoisting mechanism carried by said carriage and connected with said platform, said first-named 130

means and said mechanism being independent of each other.

8. The combination, in a truck, of a carriage consisting in part of side pieces and a cross bar provided with trunnions, a superimposed platform consisting in part of a cross piece adapted to rest on said side pieces, and of side pieces adapted to rest on said bar, transverse rods in said carriage and platform side pieces and a transverse rod in said cross piece, pivotally-connected links mounted on said trunnions and rods, wheels also on said trunnions, an independent swivel and wheel support for the front end of said carriage, and means to actuate said carriage and platform relatively.

9. The combination, in a truck, of a carriage consisting in part of side pieces and a cross bar provided with trunnions, a superimposed platform consisting in part of a cross piece adapted to rest on said side pieces, and of side pieces adapted to rest on said bar, transverse rods in said carriage and platform side pieces and in said cross piece, pivotally-connected links mounted on said trunnions and rods, said links having projecting parts for mutual engagement during a portion of the movement of said links, and said carriage side pieces having lugs arranged to limit the movement in one direction of the jointed terminals of said links, wheels also mounted on said trunnions, an independent swivel and wheel support for the front end

of said carriage, and means to actuate said carriage and platform relatively.

10. The combination, in a truck, with a carriage provided with a support, rotary hoisting members mounted in said support, and a worm and worm-wheel arranged in said support to actuate said members, of a superimposed platform, jointed links pivotally connected with said carriage and platform and adapted to raise the latter when the same is forced in one direction or said carriage is forced in the other direction, and a flexible member attached to said platform and connected with said hoisting members.

11. The combination, in a truck, with a carriage provided with a support, shafts carrying pulleys and idlers mounted in said support, a worm-wheel on one of said shafts, a worm mounted in said support and intermeshing with said worm-wheel, and a crank member for said worm, of a superimposed platform, direct lifting means between said carriage and platform, and a flexible member looped behind said pulleys and passing over the same, and under said idlers to have the ends of said flexible member attached to said platform.
